ACTUATOR

Robert W. Leland and Calvin J. Werner, Dayton,
Ohio, assignors to General Motors Corporation,
Detroit, Mich., a corporation of Delaware

Application July 19, 1944, Serial No. 545,715

12 Claims. (Cl. 268—74)

This invention relates to improvements in actuating devices and their controls.

It is among the objects of the present invention to provide an actuator particularly adapted to move an object or load from normal into operated position with a quick movement, and then to return the object or load to its normal position when desired.

A further object of the present invention is to provide an actuator which is adapted to move an object or load from its normal position into its operated position in a minimum time after control mechanism has been operated to set the actuator in motion.

The actuator of the present invention is particularly adapted to operate the bomb-bay doors of a warplane in which it is of great importance to assure quick opening of the doors substantially immediately upon the operation of a control mechanism within reach of the operator.

Further objects and advantages of the present invention will be apparent from the following description, reference being had to the accompanying drawings wherein a preferred embodiment of the present invention is clearly shown.

In the drawings:

Fig. 1 is a part sectional view of the actuator in its normal retracted or door closing position.

Fig. 2 is a fragmentary view of the actuator shown in Fig. 1, parts, however, being shown in the extended or door opening position.

Fig. 3 is a fragmentary view of a warplane having its bomb-bay doors equipped with the present invention.

Fig. 4 is a wiring diagram schematically showing the various control devices and their electrical connections and circuits.

Fig. 5 is a portion of the wiring diagram shown in Fig. 4 illustrating the switch operating cam in the position in which it will be when the nut has reached its lowermost travel to release the door actuating lever.

Fig. 6 is a similar view showing the switch operating cam in the position in which it will be when the motor reaches its uppermost position in which the door operating lever is in the door closing position.

Referring to the drawings and particularly to the Figs. 1 and 2 thereof, the actuator is shown comprising an electric motor 20 having an apertured lug 21 at its one end which forms one portion of a hinge connection by means of which the actuator is attached to the fuselage of the plane, as shown in Fig. 3. The housing of

the motor 20 is seated upon and secured to a gear housing 22 in any suitable manner. This electric motor 20 is of the type shown in the copending application of Calvin J. Werner, Serial No. 468,475, filed December 10, 1942 and comprises an armature having a shaft to which a driving disc is attached. An electromagnetic clutch as illustrated and described in the above mentioned copending application is also provided in this device, said clutch being adapted to be energized with the energization of the electric motor 20 for purposes of connecting the stub shaft 23 with the electric motor so that it may be rotated thereby. The one end of this stub shaft is journaled in a ball bearing in the motor housing as illustrated and described in said copending application, the opposite end of said stub shaft being supported by a ball bearing 24 nested in a recess provided at the inner end of the tubular screw shaft 25.

In the housing 22 there are provided two ball bearings 26 and 27 which rotatably support the annular gear 28 secured to the inner end of the screw shaft 25 by being threaded thereon and having locking pins 29 passing through the gear and screw shaft. The housing 22 contains two ball bearings 30 and 31 which rotatably support an annular gear 32 having outer peripheral gear teeth 33 at its one end and inner peripheral gear teeth 34 adjacent its other or bottom end. A worm pinion 35, secured upon a shaft journaled in the housing 22, meshes with the outer peripheral gear teeth 33 of the annular gear 32, holding said annular gear against rotation when the electric motor 20 is operated to rotate the screw shaft 25. The shaft of worm pinion 35 is adapted to be rotated manually to rotate the screw shaft 25 independently of the motor 20. This feature is thoroughly illustrated, described and claimed in the copending application of Calvin J. Werner, Serial No. 536,913, filed May 23, 1944.

The stub shaft 23 has an eccentric portion 40 upon which two roller bearings 41 and 42 are supported. These roller bearings in turn support the epicyclic gear member 43, one portion having external gear teeth 44 adapted to mesh with the internal gear teeth 34 of the annular gear 32, another portion of the epicyclic gear 43 having external gear teeth 45 meshing with the internal gear teeth 46 of the annular gear 28 which, as has previously been described, is positively secured to the inner end of the screw shaft 25.

From the foregoing it may be seen that, when the electromagnetic clutch, not shown, is energized with the energization of the electric motor

20, the electric motor is operatively connected with the stub shaft 23, rotating it so that its eccentric portion 40 will revolve the epicyclic gear 43 about its orbit. This movement of the epicyclic gear 43 in meshing with the stationary annular gears 32, will result in rotation of said epicyclic gear at a reduced rate and, in rotating, it will transmit rotation to the annular gear 28, with which a portion of said epicyclic gear is also in operative connection, thereby resulting in 10 a rotation of the screw shaft 25 at a reduced rate.

The above described portion of the present actuator is similar to the construction shown in the above identified copending applications. The new features of the present invention will now 15 be described.

At the bottom or free end of the screw shaft 25 there is secured a ball bearing member 50 having inner and outer races. The screw shaft has a helical, annular outer groove 51 throughout its length. A nut 52 fits about the screw shaft 25, the inner annular surface of the nut being provided with a helical annular groove coincident in pitch and size with the helical annular groove on the screw shaft 51. The grooves of the shaft and nut coinciding, form a helical channel in which traveling balls 53 are provided, mechanically connecting the nut with the screw shaft. Details of construction of this type of mechanical connection between a nut and a screw shaft are fully set forth in the copending application of Calvin J. Werner, Serial No. 468,475 previously referred to, and therefore no detailed description will be given in the present instance. Suffice to say that the traveling balls 53 in the helical groove between the nut and shaft provide mechanism connecting the nut to the shaft in a manner similar to an ordinary screw thread, the ball connection, in lieu of the ordinary thread however, reducing friction to a minimum.

An actuating member or shifter 60 in the form of a tubular member has its inner end secured to a collar 61, the outer or opposite end of said tubular member 60 having the anchoring member 62 secured thereto by screws 63. This anchoring member 62 has a recess 64 for receiving the attachment lug 65, Fig. 3, forming a portion of a plate 66 which is attached to the bomb-bay door 67 of the warplane 68. The anchoring member 62 has a projection 69 extending upwardly into the tubular member 60, the inner end of the projection 69 lying adjacent to a flange 70 on the nut 52 when said nut and the member 60 are on normal position. A latch 71 hingedly is secured to member 62, spring 72 urging said latch into locking engagement with the outer race member of the ball bearing 50 when the tubular member 60 is in normal position as shown in Fig. 1. The nut 52 has a tapered end portion 73 which is in almost touching proximity to the latch 71 when the nut and latch are in normal position.

A collar 75 is securely fastened to the tubular member 60 in any suitable manner as for instance by welding, screws 76 securing a tubular guide member 77 to the collar 75. In the annular space provided between the tubular member 77 and the tubular member 60 there is a heavy duty coil springs 78, one end of which rests upon the collar 75, the other end abutting against the clamping collar 79 which is threadedly secured in the lower, outer end of the gear housing 22 and also acts to maintain the bearings 27 and 26 with their internal annular gear 28 supported

in proper position in the gear housing. In the normal position as shown in Fig. 1, the heavy duty spring 78 exerts a constant force upon the collar 75 to urge the member 60 outwardly. However, this is normally prevented due to the fact that the latch 71 on the attachment member 62 of the member 60 lockingly engages the outer race of ball bearing 50 carried at the lower end of the screw shaft 25.

A dust cover tube 81 has its one end anchored to the clamping ring 79 by means of screw 82, the other end of said tubular dust cover 81 having an inner annular sealing ring 83 which wipingly engages the tubular member 77.

Fig. 3 is a fragmentary view of a battle plane fuselage having bomb-bay doors 67 and 167 hingedly attached to the fuselage and adapted to be closed by the device of the present invention. When approaching a target the operator 20 opens the bomb-bay doors 67 and 167, after which the bombardier releases the bomb illustrated at 168 at the proper moment. In order that a minimum time be consumed between the opening of the bomb-bay doors and the release 25 of the bombs, it is desirable that the bomb-bay doors open quickly, for to open the bomb-bay doors slowly or a considerable time before the bombs are released would offer appreciable resistance and affect the speed and flight of the 30 plane.

When the operator desires to open the bomb-bay doors, control mechanism is actuated whereby the electric motor 20 and the electromagnetic clutch associated therewith are energized, rendering both active and thereby causing the motor 20 to rotate the screw shaft 25 in such a direction that the nut 52 thereon will be moved longitudinally downwardly or toward the free end of the screw shaft. Inasmuch as the tapered end 73 of the nut normally engages the latch 71 which holds the door operating lever 60 in normal door-closing position, only a very slight movement of the nut 52 is necessary to move the latch 71 out of engagement with the outer race of the ball bearing 50 and thereby release the member 60 attached to the bomb-bay door. As soon as the latch 71 is moved from locking engagement with the ball race, the heavy duty spring 78 becomes effective quickly to move the member 60 from its normal position as shown in Fig. 1 into its operated or door opening position as shown in Fig. 2. When the actuator is in the position shown in Fig. 2, the bomb-bay doors are wide open as shown in Fig. 3 and the bombardier may then release the bomb 168. When the bombing operation is completed the operator again closes the bomb-bay doors 67 and 167 by moving a control device to the "up" position in which circuits are completed, causing the electric motor 20 to rotate in a direction opposite to that in which it was rotated to open the doors. Now the screw shaft 25 is rotated in the opposite direction and the nut 52 starts to move upwardly on the screw shaft 25. In its door opening position the ring 61 on the upper end of the door operating tubular member 60 normally rests upon the upper flange 152 of the nut as shown in Fig. 2; therefore as the nut 52 moves upwardly this member 60 is drawn upwardly toward the gear housing 22, thus causing the bomb-bay doors 67 and 167 to be closed. When the member 60 has been moved to full door-closing position, its latch 71 will again engage the outer race of ball bearing 50 to lock the lever in this door closing position. As soon as the nut 70 75 has reached the position in which the member

60 is latched in its door closing position, automatic control means become effective to reverse motor connections and thereby again cause the electric motor to rotate in the direction so that the screw shaft 25 will cause the nut 52 to move downwardly. When the nut 52 reaches the normal position as shown in Fig. 1, in which the tapered end 73 thereof merely engages the latch 71, another automatic means will become effective to break the motor connections and stop its operation.

Immediately after the nut has been moved to its uppermost position in which the member 60 is in its full door closing position, the motor might be stopped and permitted so to remain until it is desired to again open the doors, at which time the circuit could be completed with the motor to cause its rotation and consequent rotation of the screw shaft 25 so the nut will move downwardly toward the latch 71 and upon engaging and operating said latch 71 the member 60 could be released to render the heavy duty spring 78 operative quickly to move the lever to open the bomb-bay doors. However, with such an arrangement considerable time would be consumed in the travel of the nut from its extreme upper position to the lowermost position in which the latch 71 is released. In order to eliminate this undesirable interval of time, which might appreciably affect efficient bombing and in order to obtain immediate opening of the bomb-bay doors upon actuation of the proper control mechanism, applicants have so arranged their control devices that the motor operation is reversed when the nut reaches its uppermost position and is not stopped until the nut reaches its normal position where it merely engages latch 71, but does not release it.

The projection or extension 69 on the attachment member 62 of member 60 is provided so that as the nut moves downwardly to release the latch 71, the flange 70 of the nut may forcibly engage the extension 69 and thereby give the door operating member 60 a starting bump. This might be advantageous in case the bomb-bay doors 67 and 167 are slightly stuck in their door closing position and could not be set into immediate operation by the constantly applied opening force of the spring 78. With this slight bump given the member 60 by the flange 70, such sticking of the doors in their closed position could be readily overcome.

In order to provide automatic controls as referred to above whereby the motor 20 is caused to rotate in one direction only sufficiently to rotate screw shaft 25 so that the nut 52 moves downwardly to release latch 71 and then stop, following which control devices may be actuated to cause the motor to rotate in the opposite direction sufficiently to move the nut 52 so that member 60 is again returned to its full door closing position and so latched and then to cause a reversal of the motor automatically hereby the nut 52 is again returned to its normal position as shown in Fig. 1 and the motor operation stopped, applicants have provided an automatic circuit making and breaking device driven from the speed reducing gearing to provide properly timed control.

The annular gear 28 of the speed reducing gearing has an outwardly extending flange 100 on the outer peripheral surface of which is provided a low pitch worm tooth of approximately one and a half to two convolutions about the flange. This worm tooth engages a pinion 101 secured to a

shaft 102 which is journalled in the gear housing 22 so as to be substantially tangential to the annular gear 28. Speed reducing gearing including a series of gears 103, 104, 105, 106 and 107 connect a shaft 108 operatively with the annular gear 28 of the speed reducing gearing of the actuator. Shaft 108 operates a switch control cam 109. This switch control cam is adapted to actuate the movable contacts of the circuit control switches 110, 111 and 112, which will be detailedly described in connection with the circuit diagram for Figs. 4, 5 and 6. Illustrations of these control devices in Figs. 4, 5 and 6 are merely diagrammatic and may be of any suitable standard design which might properly perform the function to be described. The arrangement of gears 101 to 107 inclusive is also diagrammatic and may be of any suitable construction whereby the control switches are operated in properly timed sequence in accordance with the position of the nut 52 on the screw shaft 25.

The switch control cam 109 has two recesses 200 and 201 so positioned on the cam that at the proper time in its rotation certain switches will be opened and others closed to control motor operation.

The control device includes a selector switch 202 having a movable contact arm 203 adapted to be moved into electrical engagement with the terminal 204 which may be termed the "up" terminal and also moved in the opposite direction into electrical engagement with the terminal 205 which may be called the "down" terminal.

Two electromagnetic contactors are provided, the one designated by the numeral 206 being termed the "down" contactor and comprises an electromagnetic winding 207 adapted, when energized, to actuate a solenoid core 208 upon which are carried two bridging elements 209 and 210. Bridging element 209 is adapted to connect the two terminals 211 and 212, while bridging element 210 is adapted to connect terminals 213 and 214 of this contactor. The "up" contactor designated by the numeral 215 comprises an electromagnetic winding 216 adapted, when energized, to actuate the solenoid core 217 to lift the bridging element 218 into bridging engagement with the terminals 219 and 220. A lock-out relay 225 is provided, comprising an electromagnetic winding 226, adapted, when energized, to attract the solenoid core 227 and move it upwardly to break the normally engaging contacts 228 and 229 of the relay and then at the same time to cause engagement of the normally open contacts 230 and 231 of this relay.

The source of power for operating the actuator is a storage battery 235 grounded at its one side and having its other side connected to a terminal 236 of the master switch 237 whose other terminal 238 is connected with the movable contact arm 203 of the selector switch 202. The reversible motor has two field windings 240 and 241, each of which, when energized, causing the electric motor to operate in a respective direction when it is energized. The electromagnet clutch previously mentioned comprises an electromagnet winding 250 which, when energized, will energize the driving disc 251 operatively connected with the shaft of the motor armature so that it may attract the movable armature 252 which is operatively connected with the stub shaft 23 of the speed reducing gearing. When the motor and the electromagnet clutch are not energized and therefore the driving disc 251 of the motor is not energized, the armature 252 is held in frictional

engagement with a braking ring 254 supported within the gear housing 22 in any suitable manner. Thus normally the screw shaft and its speed reducing gearing are held against rotation under the effect of the weight of the doors acting upon the screw shaft through the nut. 5

The various active circuit connections during the different phases of door operation will now be described. Normally the bomb-bay doors 67 and 167 are closed so that they will conform to the contour of the body of the plane fuselage. When it is desired to open the door preparatory to releasing bombs 168, the operator at any time previously thereto has closed the master switch 237 which connects the storage battery or power source 235 with the selector switch 202. To open the doors, the operator moves the movable contact member 203 clockwise into engagement with the stationary terminal 205 of said switch, thereby completing the following circuit: from the battery across the terminals 236 and 238 of switch 237 through the movable contact 203 of selector switch 202 to the terminal 205 thence through wire 260 to the juncture point 261 from whence the current will flow through the wire 262, the movable contact 113 across the two contacts 263 of the switch 110, the contacts 264 of said switch being open due to the fact that the rubber block of the movable contact arm 113 is riding upon a high spot of the cam 109 which is now immovable. From switch contacts 263 the current flows through the wire 265 through the electromagnet winding 207 of the "down" contactor 206 thence back to the source of power via the ground connections. Energization of the electromagnet winding 207 will cause the solenoid core 208 thereof to be moved upwardly, shifting the bridging elements 209 and 210 into bridging engagement with their respective stationary terminals, thereby closing the following circuits: from the source of power 235 across the switch 237 to the juncture point 266 thence to the terminal 211, bridging element 209, terminal 212 through wire 267 to the juncture point 268 thence through the motor field 241, wire 269 to terminal 213 of the "down" contactor, thence across its bridging member 210 to the terminal 214 and back to the source of power via the ground connections. A portion of this current flow will leave the juncture 268, flow through the wire 270 to the juncture 271 from whence a divided circuit is established, one through the armature windings of the motor to ground, the other through the electromagnet clutch winding 250 to ground. With all of these circuits completed, the electromagnet clutch is energized to move the armature 252 into operative engagement with the motor driving disc 251 which is now being rotated in one direction due to the energization of the motor field 241 and armature circuits. This rotation of the motor is such as to cause rotation of the screw shaft 25 to move the nut 52 thereon downwardly so that its bevel end 13 actuates the lock-in latch 71 out of locking engagement with the outer race of the ball bearing 50 thereby releasing the door operating member and permitting the heavy duty spring 78 to be active quickly to shift the bomb-bay doors widely open. 60

As the electric motor and consequently the speed reducing gearing and the screw shaft 25 are rotated to move the nut downwardly, the gear 28 of the speed reducing gearing is actuating switch operating cam 109 in a clockwise direction through the timing gear connections. As soon 75

as the nut 52 is moved downwardly to release the door operating member latch 71 and thereby render the spring 78 effective, the cam 109 will have reached a position in which the rubbing block on the movable contact arm 113 of switch 110 enters into the recess 200 of cam 109, thereby permitting the contacts 263 of this switch to be separated and the contacts 264 of this switch to be engaged. Separation of contacts 263 breaks the circuit through the electromagnet winding 207 of the down contactor 206, thereby deenergizing the contactor and causing it to drop to circuit breaking position in which the bridging elements 209 and 210 are moved out of engagement with their respective stationary terminals and consequently break the motor circuits and stop its operation. The closing of contacts 264 will render a circuit including a light 272 active as soon as switch 273 is closed by the bomb-bay doors reaching their wide open position. Thus when the bomb-bay doors are widely open, the light 272, visible to the operator will indicate that the bomb-bay doors are wide open and that bombs may be released. The positions of switches 110, 111 and 112 under these circumstances are clearly illustrated in the Fig. 5. Switches 111 and 112 are inactive electrically during this phase of the actuator operation. 15

As soon as the dropping of the bombs has been completed and the operator desires to again close the bomb-bay doors 67 and 167, he will actuate the movable contact 203 of the selector switch 202 counterclockwise so that said movable contact 203 is disengaged from terminal 205 and moved into electrical engagement with terminal 204. Now the following circuits are completed: from the source of electrical power 235 across the terminals 236 and 238 of switch 237 to the movable contact arm or member 203 of the selector switch through terminal 204, wire 300 to the juncture point 301, thence through wire 302 to the movable contact arm 111a of the switch 111 across its now closed contacts 303 through wire 304 thence across the engaging contacts 229 and 228 of the relay 225, through wire 305, electromagnet winding 216 of the up contactor 215 back to the source of power via the ground connections. Energization of the electromagnet winding 216 will cause the raising of the solenoid core 217 and its bridging element 218 whereby contacts 220 and 219 are connected together to establish the following circuit: from the source of power 235 across switch 237 to the juncture point 306, thence from terminal 220 to terminal 55 219 via the bridging element 218, wire 307, motor field 240 to the juncture 308 thence to the juncture 271 where a divided circuit through the armature and through the electromagnet 250 back to the battery via ground connections will be established. 60

With these motor connections completed, the motor 20 will now rotate in an opposite direction, that is opposite to the direction it rotates in response to the closing of the down contactor 206. 65 As the motor rotates in this opposite direction, its connection with the screw shaft 25 through the electromagnetic clutch and speed reducing gearing previously mentioned will rotate said screw shaft so that the nut 52 will be moved upwardly toward the upper inner end of the screw shaft. 70

When the doors are opened, the actuator parts assume relative positions as shown in Fig. 2, that is, the ring 61 of the door operating member 60

rests upon the flange 152 of the nut 52. Now as the nut is moved upwardly in response to reverse operation of the screw shaft 25, it will carry with it the door operating tubular member 60 whereby moving the door attached thereto into its closed position, this position being reached when the nut 52 has moved the lever so that the latch 71 again lockingly engages the outer race of the ball bearing 50, as shown in Fig. 1. As the motor speed reducing gearing and screw shaft 25 rotate in this reverse direction, the gear 28 of the speed reducing gearing will, through the timing gears shown in Fig. 4, actuate the switch operating timer 109 counterclockwise so that the rubbing block on movable arm 113 of switch 110 will leave the recess 200 and again ride the high surface of cam 109, thus again opening contacts 264 of switch 110 and closing its contacts 263. At the same time the rubber block on the movable contact arm 112a of the switch 112 will ride the high portion of the cam so that the normally open contacts 306 thereof will be closed and the normally closed contacts 307 of switch 112 will be opened. As soon as the nut 52 reaches its uppermost position on the screw shaft, in which position the door actuating tubular member 60 is again latched in door closing position, the cam 109 will have been moved to assume the position as shown in Fig. 6 where the recess 201 thereof will lie adjacent the rubbing block of the movable contact arm 112a of the switch 112. Now this rubbing block will enter the recess 201, permitting the movable contact arm 112a to move to open the contacts 303 of switch 111 and to close the contacts 308 thereof as shown in Fig. 6.

Separation of contacts 303 breaks the circuit flowing across contacts 228 and 229 of the relay 225 and consequently the circuit through wire 305 and the up contact winding 216, thereby de-energizing the up contactor and permitting it to fall into circuit-breaking position in which contactors 219 and 220 thereof are disconnected one from the other, thereby breaking the motor circuit to stop motor operation. Now the motor ceases to operate in this reverse direction, however, with the closing of contacts 308 of the switch 111 and the closing of contacts 306 of switch 112 due to the position of the cam 109 as shown in Fig. 6, which is the position of said cam when the motor ceases its reverse direction, the following circuits will be established: from the source of current 235 across switch 237 to the movable contact arm 203 of the selector switch 202, thence through terminal 204 still engaged by said arm 203 through wire 300 to the juncture point 301, thence through wire 302 across the now engaging contacts 308 of switch 111 through wire 309 to the movable contact arm 112a of the switch 112 across the now closed contacts 306 of said switch 112, thence through the wire 260 to the juncture point 261, thence thru the wire 262, contact arm 113 of the switch 110 across the now closed contacts 263 of the switch 110, wire 265, electromagnet winding 207 of the down contactor 206 back to the source of current via the ground connections. Energization of the down contactor winding 207 will effect actuation of the contactor to bridge its stationary contacts 211—212 and 213—214 via the bridging elements 209 and 210 respectively thereby again establishing the motor circuit so that the motor will operate in its original direction, that is in a direction to actuate the screw shaft 25 so that the nut 52 thereon moves downwardly. It will be seen that this is

automatic and requires no operation of any device by the operator after he once has actuated the selector switch into the up position initially to move the nut from its lowermost position as shown in Fig. 2 to the uppermost position in which it has just moved the door operating member 60 into full door closing position.

At the same time, closing of contacts 308 of the switch 111 completes a circuit from the juncture point 301 through wire 302 across contacts 308 through wire 309 thence through wire 310 to juncture point 311 thence through the electromagnet winding 226 of the lock-out relay 225, energization of winding 226 will cause the solenoid core 227 thereof to be moved upwardly to break contacts 228 and 229 and engage contacts 230 and 231. With the closing of contacts 230 and 231 current can then flow from the source across the switch 237, selector switch contact 203, terminal 204, through wire 300 thence across contacts 230—231 to juncture point 311 and thence across the magnet winding 226 thereby holding said relay in a position to maintain the contacts 230 and 231 in circuit with the up contactor winding 216 open.

As the motor speed reducing gearing and screw shaft 25 rotate to move the nut 52 downwardly and to rotate the switch operating cam 109 clockwise, said cam 109 will eventually reach its original position as shown in Fig. 4. However before the extreme down position of the nut is reached, or shortly after the motor starts on its directional rotation to move the nut downwardly, contacts 308 of switch 111 will again be broken and contacts 303 thereof be engaged. With the breaking of contacts 308, the original circuit across them and through the lock-out relay winding is broken, however, the other circuit through this winding 226 is maintained due to the fact that contacts 230 and 231 are held closed and a circuit across them and through the lock-out relay winding 226 is maintained. Therefore the circuit across the contacts 306 of switch 112 and contacts 263 of switch 110 to the down contactor winding 207 is maintained to permit the motor circuits to be retained for purposes of continued motor operation to move the nut downwardly.

When the nut reaches its normal position as shown in Fig. 1, in which its bevel edge 73 merely engages the latch 71, the cam 109 will have been operated into the position as shown in Fig. 4 so that contacts 306 of switch 112 are disengaged. With the separation of these contacts 308 the circuit including contacts 263 of switch 110 and the winding 207 of down contactor 206 are concurrently broken and therefore the contactor 206 is deenergized to permit it to drop to circuit-breaking position, thereby breaking the motor circuit and stopping motor operation in this direction. Now all elements of the actuator and its control mechanism with the exception of the selector switch contact arm 203 are in their normal position as contact 203 may still be kept in engagement with the terminal 204 to complete the following circuit without effecting movement of any element of the device: from the battery across switch 237, selector switch arm 203 and its terminal 204, wire 300, contacts 230—231 through the magnet winding 226 of the lockout relay 225 to maintain contacts 230 and 231 closed, also from contacts 230—231, juncture point 311 through the wire 310, across contacts 307 of switch 112 thence through the indicator light

315 and across contacts 316, which are maintained closed when the bomb-bay doors are closed, thus indicating to the operator that the actuator has closed the bomb-bay doors. When the operator moves the lever 203 to its neutral position as shown in Fig. 4, all circuits are open.

From the foregoing it will be seen that applicant has provided an actuator for operating the bomb-bay doors of a warplane, said actuator being adapted to move the doors from normally closed into operated open position with a quick movement and in a minimum interval after mechanism, the switch 202, has been operated to set the actuator in motion.

The control mechanism is actuated into one position to cause opening of the doors and then the system ceases operation. The control mechanism is then operated to close the doors, the motor actuating the screw to move the nut upwardly for purposes of pulling the doors into closed position, then the control mechanism acts automatically to cause reversal of the motor for purposes of returning the nut downwardly into its normal position. Downward movement will be stopped when the nut reaches its normal position and before it has moved beyond its normal position in which it will again release the doors to permit their being opened by the heavy-duty spring which actually provides the power for opening the doors.

While the embodiment of the present invention as herein disclosed, constitutes a preferred form, it is to be understood that other forms might be adopted, all coming within the scope of the claims which follow.

What is claimed is as follows:

1. In a device of the character described, the combination with a closure member adapted to be moved from closing into open position with a quick action; a spring loaded shifter connected to the closure member and operative to actuate said member; a latch engaging said shifter and releasably holding it in spring loaded position in which the closure member is maintained in closing position; a screw shaft with a non-rotatable nut threaded thereon and movable axially thereon in response to rotation thereof; means on said nut being operative, in response to axial movement on the nut in one direction; on the screw shaft, first to engage the latch and release said shifter and second to strike said shifter and start it on its spring actuated movement completely to move the closure member to full open position, other means on said nut, operative in response to axial movement of the nut in the opposite direction on the shaft directly to engage the shifter and return it into normal spring loaded and latched position; and means for rotating the screw shaft in either direction.

2. In a device of the character described, the combination with a load adapted to be moved between two positions; a screw shaft; a nut threadedly carried by said screw shaft; a spring loaded member carrying the load; a detent on the screw shaft; a latch on the spring loaded member, operative to engage the detent and lock said member in normal, spring loaded position; means on said member engaging the nut to prevent its rotation but permitting relative longitudinal movement on the screw shaft; means for turning the screw shaft in either direction to effect longitudinal movement of the nut on the screw shaft; means on the nut operative as it moves in one direction, to engage the latch and release the spring loaded member for quickly shifting the

load into fully operated position; means on the nut, operative as said nut moves in the opposite direction, directly to engage the spring loaded member and return said member to its normal, spring loaded position in which the load is in its normal position.

3. In a device of the character described, the combination with a hinged door; a screw shaft; a nut threaded to said shaft; a tubular member surrounding said screw shaft, one end of said member being attached to the door; a sliding key connection between the nut and member to prevent rotation of the nut; a latch on the tubular member, engaging the screw shaft and releasably holding the member in door closing position; a coil spring engaging the member and exerting a constant force thereupon to urge it toward the door opening position; and means for rotating the screw shaft, in one direction to cause the nut to move into engagement with the latch to release the tubular member whereby said spring may actuate it to open the door, and in the other direction to cause the nut to engage and move said member to compress the spring, actuate the door into its closed position and again establish engagement of the latch with the screw shaft.

4. In a device of the character described, the combination with a load adapted to be moved between normal and operated positions, of a spring loaded shifter attached to the load and latched in normal position; a screw shaft threadedly supporting a nut; means on the shifter engaging the nut to prevent its rotation but permitting longitudinal movement thereof, said nut, when moving in one direction, being operative to unlatch and release the shifter to permit it to move the load quickly from normal to completely operated position, and operative when moved in the opposite direction directly to engage and move said shifter to lift the load and return it to its normal position; and means for turning the screw shaft to effect longitudinal movement of the nut in either direction.

5. In a device of the character described, the combination with a door adapted to be moved from closing into open position with a quick action, of a spring loaded shifter adapted to actuate said door into open position; a latch normally holding said shifter in door closing position; a screw shaft having a nut threadedly mounted thereon said nut being held against rotation and being movable longitudinally on said screw shaft by rotation of the shaft; a reversible electric motor; means for connecting the electric motor with the screw shaft to rotate it in either direction, whereby the nut is moved first to engage the latch and release the spring loaded shifter to move the door into open position in response to rotation of the screw shaft in one direction and second to engage and actuate the shifter to lift the door into its closing position; and control means for effecting operation of the electric motor in either direction.

6. A device in accordance with claim 5 in which, however, the nut is normally located on the screw shaft in close proximity to the latch which holds the shifter in door closing position whereby only several turns of the screw shaft are required to move the nut to engage the latch and release the shifter; selective control means adapted to be actuated to effect rotation of the electric motor in one direction or the other; and automatic control means for reversing the operation of the electric motor after it has actuated the screw shaft to move the nut into a position in which

the shifter has closed the door and for stopping this reversed motor rotation when the nut has reached its normal location on the screw shaft.

7. In a device of the character described, the combination with a normally closed door; a spring loaded tube for operating the door; a latch holding the tube in door closing position; a screw shaft; a nut threadedly carried by the screw shaft and normally engaging the latch; means connecting the nut to the tube to permit relative longitudinal movement therebetween but preventing rotation of the nut; a reversible electric motor adapted to drive the screw shaft in one direction to actuate the latch to release the tube and to strike said lever to start it on its door opening movement, said motor being adapted to drive the screw shaft in the opposite direction whereby the nut will engage and move the lever into its latched, door closing position; and means for controlling operation of the electric motor.

8. A device in accordance with claim 7 in which, however, there is provided control mechanism including a selector switch adapted to be operated into one position to effect operation of the motor to rotate the screw shaft so that the nut thereon moves to engage the latch and release the spring loaded tube; a circuit breaker adapted to stop motor operation when the latch is released; timer means driven by the motor to actuate said circuit breaker; control devices rendered effective by the operation of the selector to another position to effect operation of the electric motor to rotate the shaft so that the nut thereon moves to shift the tube into its normal latched, door closing position; means for reversing the rotation of the electric motor when the tube is moved into its latched position; and means for stopping the motor when the nut reaches its normal, latch engaging position, said reversing means being automatically controlled by the motor driven timer means.

9. In a device of the character described, the combination with a normally closed door; of a spring loaded tubular member for operating said door; a latch normally holding the member in the door closing position; a screw shaft; a nut threadedly to said screw shaft and normally engaging the latch; means on the tubular member for preventing rotation of the nut but permitting relative longitudinal movement between the nut and the member and screw shaft; a reversible electric motor; speed reducing gearing for connecting the electric motor with the screw shaft; control mechanism for effecting operation of the electric motor in one direction to rotate the screw shaft for moving the nut to actuate the latch and release the spring loaded member to open the door, and for effecting operation of the electric motor in the other direction for moving the nut to engage and actuate the member into its normally latched, door closing position; a control device for stopping motor operation when the nut has released the member to open the door; a second control device for reversing motor operation when the nut has returned the member to its normal door closing position; a third control device for stopping motor operation when the nut is moved into its normal latch engaging position; and a common means, driven by the speed reducing gearing for actuating said three mentioned control devices in proper time and sequence.

10. In a device of the character described, the combination with a normally closed door; of a spring loaded tubular actuator for operating said door; a latch normally holding the actuator in the door closing position; a screw shaft; a nut threaded to said screw shaft and normally engaging the latch; means on the actuator for preventing rotation of the nut but permitting relative longitudinal movement between the nut and the actuator and screw shaft; a reversible electric motor; speed reducing gearing for connecting the electric motor with the screw shaft; control mechanism for effecting operation of the electric motor in one direction to rotate the screw shaft for moving the nut to actuate the latch and release the spring loaded actuator to open the door, and for effecting operation of the electric motor in the other direction for moving the nut to engage and move the actuator into its normally latched, door closing position; a control device for stopping motor operation when the nut has released the actuator to open the door; a second control device for reversing motor operation when the nut has returned the actuator to its normal door closing position; a third control device for stopping motor operation when the nut is moved into its normal latch engaging position; a single cam for operating the said, last mentioned three control devices in proper time and sequence; and driving connections between the cam and speed reducing gearing.

11. A unitary device for moving a load between normal and operated positions, comprising in combination, a shifter attached to the load; a detent engaging the shifter to lock it in the normal position; a spring engaging the shifter and urging it toward the operated position; a prime mover capable of reverse rotation; a screw shaft rotated by said prime mover; a non-rotatable nut threaded to said screw shaft and movable axially thereon, in response to rotation of the shaft in one direction, to engage and actuate the detent to release the shifter whereby the spring quickly thrusts the shifter and its load into fully operated position, said nut moving axially on the screw shaft in response to reverse rotation thereof, directly to engage and return the shifter and its load into detent engaging, normal position.

12. In combination with a reversible prime mover, of a screw shaft driven thereby, a non-rotatable nut threadedly secured to the screw shaft and movable axially thereon in response to rotation thereof; a load carrying shifter; a spring urging the shifter into one position; means on the shifter engageable by the nut for moving the shifter into a second position and compressing the spring as said nut moves axially on the screw shaft in response to rotation thereof in one direction; a detent engaging the shifter and operative to lock said shifter in its second, spring compressing position; and means on the nut for engaging and actuating the detent completely to release the shifter and render the spring effective to move the shifter fully into its said one position in response to axial movement of the nut on the screw shaft as it rotates in the opposite direction.
